a corporation of California

Application May 28, 1940, Serial No. 337,624

3 Claims. (Cl. 271—2.3)

This invention relates to dispensing devices for toweling and the like.

An object of the invention is to provide a dispensing device for toweling which has an arresting means for arresting the discharge of toweling after a predetermined length thereof has been discharged and which requires a manual operation to effect a release of the toweling to permit of a subsequent withdrawal. In the preferred form of construction the manual operation consists of a slight reverse rotation of the measuring roll over which the toweling is trained.

Toweling dispensing devices have heretofore been designed wherein the toweling has its discharge or withdrawal arrested after a predetermined length thereof has been removed. Time delay mechanisms have been embodied therein which delays the release of the toweling for subsequent withdrawal until a predetermined length of time has elapsed. We have experienced that the time delay mechanisms are frequently rendered useless in such devices by reason of the fact that unauthorized persons either mutilate or destroy the time delay mechanism or adjust it in such a manner that it will not function properly or will function so rapidly after the arrest of the toweling that for all practical purposes the construction operates as if the toweling had not been arrested. When either of these contingencies occur the value of the towel dispensing device is largely destroyed in that users of the towels are able to readily withdraw from the dispenser large amounts of toweling which are more than are necessary for their uses.

It is therefore a specific object of the invention to provide a dispensing device for dispensing toweling having an arresting mechanism which will arrest the discharge of the toweling when a predetermined length thereof has been withdrawn and which will keep the toweling arrested until a conscious manual operation is made to effect a release. The construction may or may not have incorporated therein a time delay mechanism which will require a predetermined length of time to elapse between successive withdrawals of toweling but where such a time delay mechanism is incorporated, even though the time delay mechanism is mutilated, destroyed, or removed, the arresting mechanism is such as to prevent the toweling from being continuously withdrawn in more than the desired length. With the improved arrangement, even if the time delay mechanism is removed by unauthorized persons a conscious effort must be made on the

part of the user to secure a succeeding towel and in this way some saving of the toweling is effected.

More specifically an object of the invention is to provide a dispensing device for toweling wherein the toweling is trained over a measuring roll which operates a rotary stop that is arrested when a predetermined length of toweling is withdrawn and to provide a mechanism which will require a slight rotation of the measuring roll in reverse direction to effect a release. The mechanism may or may not be equipped with an automatic "kick out" or a means which is loaded on rotation of the measuring roll and which serves to automatically advance or forwardly rotate the measuring roll upon its release.

With the foregoing and other objects in view, which will be made manifest in the following detailed description and specifically pointed out in the appended claims, reference is had to the accompanying drawings for an illustrative embodiment of the invention, wherein:

Figure 1 is a partial view in vertical section taken just inside of the front cover or front wall of the dispenser embodying our invention;

Fig. 2 is a horizontal section taken through the dispenser and may be considered as taken substantially upon the line 2—2 upon Fig. 5;

Fig. 3 is a view in side elevation of the internal working construction of the dispenser and may be regarded as taken substantially upon the line 3—3 upon Fig. 2 in the direction indicated;

Fig. 4 is a view similar to Fig. 3 but illustrating the parts as having been moved from the arresting position shown in Fig. 3 to the position which they assume immediately after release;

Fig. 5 is a sectional view taken substantially upon the line 5—5 upon Fig. 1;

Fig. 6 is a view similar to Fig. 3, but illustrating the parts in the position assumed when discharge of toweling is arrested;

Fig. 7 is a view similar to Fig. 3 but illustrating a slightly modified form of construction;

Fig. 8 is a view similar to Fig. 7 illustrating a slightly modified form of construction;

Fig. 9 is a plan view illustrating an alternative form of construction embodying the present invention; and

Fig. 10 is a view similar to Fig. 3 but illustrating the arresting mechanism employed in the modification illustrated in Fig. 9.

Referring to the accompanying drawings wherein similar reference characters designate similar parts throughout, the improved dispensing device in its preferred form is housed within

a suitable cabinet having a back wall 10, a cover 11, a bottom wall 12, and end walls 13 and 14. The cover, front wall and end walls are pivotally mounted as at 14a to enable opening of the dispenser for refilling purposes. Inwardly of the end walls there are partitions 15 and 16. In the bottom wall 12 there is formed an outlet opening 17 for the toweling T which is trained over a measuring roll 18 rotatably mounted between the partitions. A pinch roll or follower roll 19 has trunnions slidably disposed in slots 20 in the partitions and this pinch roll or follower roll is urged upwardly into engagement with the measuring roll by means of a spring 21. The arrangement of the slots 20 with respect to the measuring roll is to cause the pinch roll or follower roll to firmly engage the end of the toweling T that is trained over the measuring roll. The measuring roll may be grooved and the bottom wall 12 may extend upwardly as indicated at 22, the portions entering the grooves so as to strip the toweling from the measuring roll in the event that there is any tendency for the toweling to follow around the measuring roll.

The toweling is supplied to the machine in the form of a roll of paper toweling and in the preferred form of construction it is supported on supporting rails 24 and 25 mounted on the inner faces of the partitions. Adjacent the top of the partition 16 there is an inwardly extending stud 26 which extends inwardly a distance substantially equal to the width of rail 24. We prefer to groove one end of the toweling supply roll with a diametrical groove 27 through which the stud is capable of passing. This supply roll fits snugly between the partitions and the arrangement of the parts is such that on installing the supply roll the groove 27 must slip over the stud. In this way the installation of unauthorized rolls in the device is prevented, and if rolls are attempted to be installed which are so short as not to engage the stud 26, these rolls will also be so short as to be incapable of being supported by the inclined rails 24 and 25.

The invention primarily concerns the mechanism illustrated in various positions in Figs. 3, 4, and 6. On the end of the measuring roll which extends through partition 15 there is mounted a spur gear 28 which meshes with a gear 29 rotatably mounted on the partition 15. Struck out of the body of the gear 29 is a rotary stop 30 which rotates upon the rotation of the measuring roll and as the toweling T is dispensed. A cam shaft lever 31 is pivotally mounted as at 32 and provides a pivoted or movable stop 33 which can be moved into and out of the path of the rotary stop. The lever 31 is also equipped with a finger 34 adapted to be engaged by the rotary stop 30. The lever 31 is urged in a clockwise direction by means of a spring 35 which is anchored to the partition 15. The rear end of the lever extends laterally through a slot 36 in the back of partition 15 and carries a plate 37 adapted to seat upon the vacuum cup 38. 39 indicates the handle of a needle valve which controls the rate at which air may flow through plate 37 to break the vacuum in the vacuum cup 38 when the plate 37 is seated thereon.

In the top edge of the lever 31 there is formed a shoulder 40 which is adapted to be engaged by a pivoted latch 41 pivoted as at 42 and which carries a pivoted back-up pawl 43 engageable with the teeth of gear 29. A spring 44 is anchored at any suitable point on the partition and is connected by a link 45 to a pivot 46 on gear 29. The

pivot is so arranged that when the stops 30 and 33 are engaged to arrest withdrawal of toweling that the spring will be tensioned or loaded and will be urging rotation of gear 29 in that direction that will bring about forward rotation of the measuring roll.

Beneath the pinch roll 19 and above the outlet opening 17 there is a severing knife or cutter 47 against which the toweling T may be drawn to sever the projected portion of the toweling from that portion of the toweling which is still within the housing. Between partition 16 and end wall 14 a handle or knurled disc 48 is mounted on the measuring roll, the forward portion of which projects through the cover of the housing so as to be manually operable.

The operation and advantages of the above-described construction are as follows. Fig. 5 illustrates the position of the toweling when the arresting mechanism is in the position shown in Fig. 3. In Fig. 3 it will be noted that the plate 37 has been released by the vacuum cup 38, it being assumed that a predetermined period of time has elapsed so as to permit the required volume of air to enter past needle valve 39 to completely destroy or break the vacuum in the vacuum cup. In this position the stops 30 and 33 engage holding the measuring roll against advance rotation even though it is so biased by spring 44. Lever 31 is held in that position despite the release of the time delay mechanism formed by plate 37 and vacuum cup 38, because of latch 41 remaining in engagement with shoulder 40. When it is desired to obtain a towel from the device the handle or knurled disc 48 is reversely rotated a short distance producing reverse rotation of the measuring roll and of gear 28. This produces clockwise rotation of gear 29 and causes pawl 43 to lift the latch 41 out of engagement with shoulder 40. As soon as latch 41 is disengaged from shoulder 40, spring 35 swings lever 31 from the position shown in Fig. 3 to the position shown in Fig. 4, thus swinging the pivoted or movable stop 33 out of the path of the rotary stop 30. Upon release of the handle or knurled disc 48, spring 44 then becomes effective to automatically bring about a short advance rotation of the measuring roll to cause the end of the toweling T to be projected through the outlet opening 17. The projecting portion of the toweling may then be grasped and pulled to withdraw a complete towel length. The withdrawal of the toweling causes continued rotation of the measuring roll and consequently a continued rotation of gear 29 in a counter-clockwise direction. As gear 29 rotates the rotary stop 30 engages finger 34 tilting lever 31 against the action of spring 35 and causes the plate 37 to seat upon the vacuum cup as indicated in Fig. 6. In this position it will be noted that latch 41 has dropped on the top edge of lever 31 so as to be engageable with shoulder 40. The withdrawal of toweling is arrested when the rotary stop 30 again engages the pivoted stop 33. When the toweling is arrested it may be pulled against the severing knife 47 to detach the withdrawn portion of the toweling. When a predetermined length of time has elapsed plate 37 will be released by the vacuum cup and will return from the position shown in Fig. 6 to the position shown in Fig. 3, thus completing one entire cycle of operation.

It will be noted that in this form of construction that the measuring roll is not released merely by the release of plate 37 by the vacuum cup 38, but that in addition thereto, latch 41 must be dis-

engaged from shoulder 40. This requires a slight reverse rotation of the measuring roll by handle 48 a sufficient distance to cause gear 29 to be rotated the required amount to have pawl 43 lift latch 41 above shoulder 40 to enable spring 35 to swing lever 31 into the position shown in Fig. 4. Consequently, as the mechanism is to a certain extent independent of the time delay means, it is manifest that if the time delay means becomes faulty in operation or is mutilated or destroyed or adjusted so as to be practically instantaneous in its operation, that nevertheless it is impossible to withdraw the toweling in the form of a long continuous sheet. On the contrary, after each operation the toweling is definitely arrested requiring manual reverse rotation of the handle or knurled disc 48 to effect a release of lever 31 by latch 41. In this way, instead of running the risk of towel users quickly emptying the dispenser by the withdrawal of a long sheet of toweling upon failure of the time delay means conscious effort must be exerted for each towel removed. Of course, when the time delay mechanism is functioning properly the lever 31 will be held in the position shown in Fig. 6 for a predetermined length of time following each withdrawal regardless of reverse rotations imparted to the measuring roll by handle 48. Consequently, when the time delay mechanism is functioning properly a predetermined length of time is required between successive withdrawals.

In Fig. 7 the mechanism illustrated is substantially the same as that previously described but illustrating the adaptability of the device to be used without any time delay mechanism whatsoever. In this form of construction the rear end of lever 31 is cut off and the time delay mechanism is omitted entirely, otherwise all parts are the same in operation as that previously described and are consequently given the same reference characters.

In Fig. 8 the construction illustrated is the same as that illustrated in Fig. 7 with the exception that link 45 and spring 44 are omitted. The remaining parts are given the corresponding reference characters. In operating this form of construction there will, of course, not be an automatic "kick out" or automatic rotation of the measuring roll which will cause the free end of the toweling to be automatically projected through the outlet opening 17 upon reverse rotation of the handle or disc 28. In this form of construction, after the disc 48 has been reversely rotated to lift and disengage the latch 41 the handle must then be manually rotated in a forward direction to bring about a projection of the free end of the toweling T through the outlet opening 17. After it has been projected a short distance it may then be grasped and pulled to withdraw a complete towel, the operation of the various elements illustrated in Fig. 8 being the same as that previously described.

In Figs. 9 and 10, the measuring roll 50 has a pinch roll 51 and the pinion or spur gear 52 meshes with gear 53 which is the same form of gear as gear 29. Lever 54 is the same form of lever as lever 31 and has the time delay mechanism 55. The lever is urged in a clockwise direction by means of spring 56 and is equipped with a latch 57 having a pawl 58. The pawl is here shown as equipped with a spring 59 attached to the bracket 60 which acts as a stop limiting the upward movement of the latch. The use of spring 59 on all forms of construction is optional. The form herein illustrated has gear 53 mounted on the end

of a crank 61. The operation however is substantially the same as that previously described. When it is desired to withdraw a towel crank 61 is reversely turned a sufficient distance to cause gear 53 to be reversely rotated and to make pawl 58 lift the latch 57 to release lever 54. Crank 61 then is turned forwardly causing gear 53 to drive pinion 52 and to rotate the measuring roll 50 to bring about the discharge of toweling. In this form of construction, while it is possible to grasp the projected end of the toweling and to pull it from the device after withdrawal has been started, it is customary to completely crank out the desired towel length. As gear 53 rotates its stop 62 engages the finger 63 to tilt the lever 54 and seat the time delay means 55. As rotation continues the stop progresses to the point where it engages the movable stop 64 where rotation is arrested. For a subsequent withdrawal the crank must be reversely rotated a short distance as previously described.

From the above-described construction it will be appreciated that an improved toweling dispenser is provided which although it may embody a time delay mechanism, is advantageous in that arrest of the discharge of toweling is not dependent upon the present or proper operation of the time delay means. Even though the time delay means should get out of order or be destroyed or improperly adjusted, the arrest of toweling is assured at each operation of the machine requiring a conscious manual exertion to effect a release and permit subsequent withdrawal of the toweling. In those forms having a time delay means which is in proper working order a predetermined interval of time is required to elapse between successive operations. In those forms equipped with spring 44 and link 45 there is the additional advantage that when release is effected by the small reverse rotation that the free end of the toweling is automatically projected into a position to be grasped to enable its subsequent withdrawal.

It will be noted that in those forms of construction which employ time delay means it is possible to reversely rotate the measuring roll during the time delay period and thus to lift the latch 41 out of engagement with shoulder 40. Usually, the setting of the needle valve is such that as soon as the latch is lifted the vacuum cup tends to expand and allow a very slight movement of the lever 31 under the action of the spring 35. This movement, even though slight, is such that when the latch is thus temporarily lifted it will drop back on top of lever 31 in back of shoulder 40 and remain there until the vacuum cup is completely released. Upon release of the vacuum cup under these circumstances the automatic discharge means formed by spring 44 becomes immediately effective. Consequently, from the above-described operation a towel user may manually disengage latch 41 immediately after securing a towel and an automatic discharge will subsequently take place as soon as the time period has elapsed. If the towel user does not manually disengage latch 41 immediately after securing his towel, the time period elapses and then a manual operation is required to disengage the latch.

Various changes may be made in the details of construction without departing from the spirit or scope of the invention as defined by the appended claims.

We claim:

1. In a toweling dispenser, a gear carrying a

rotary stop rotatable as the toweling is dispensed, a pivoted stop movable into and out of the path of the rotary stop to arrest discharge of the toweling, latch means for latching the pivoted stop in the path of the rotary stop, and means for disengaging the latch operable upon reverse rotation of the gear.

2. In a toweling dispenser, a gear carrying a rotary stop rotatable as the toweling is dispensed, a pivoted stop movable into and out of the path of the rotary stop to arrest discharge of the toweling, latch means for latching the pivoted stop in the path of the rotary stop, and means for disengaging the latch operable upon reverse

rotation of the gear comprising a back-up pawl engageable with the teeth of the gear and operatively connected to the latch.

3. In a towel dispenser, a rotary stop rotatable as the toweling is dispensed, a pivoted stop movable into and out of the path of the rotary stop, latch means engageable with the pivoted stop upon movement of the pivoted stop into the path of the rotary stop, and means operable upon reverse rotation of the rotary stop for disengaging the latch means to release the pivoted stop for movement out of the path of the rotary stop.

MAURICE E. MALTBY.
